PUPPET HEAD

Karl Friedrich Brill, Sterkrade, Germany

Application March 24, 1930, Serial No. 438,558,
and in Germany March 27, 1929

10 Claims. (Cl. 82—31)

This invention relates to a puppet head which is especially suited for lathes designed to work large and heavy works.

When turning off works alterations of the length of the work occur owing to the heating connected with the cutting off of chips and owing to the tensions.

As the tendency is, to obtain always greater chip thicknesses by means of high grade tool 10 steels, the alterations of length are further increased. They call forth more or less great forces, which have to be taken up by the center of the puppet head and by the face plate and express 15 themselves in increased stressing of the driving spindle, puppet head bearing and increased power demand. A deformation of the work itself, especially of long works, is further caused, which unfavorably influences the accuracy of the working. Especially the dead center is being destroyed very 20 soon owing to the increased friction.

This invention has for its object the avoidance 25 of the said inconvenience by taking into consideration in the construction of the puppet head the alterations in length of the work occurring during the treatment, the facilitating of the fixing of the work by reducing the force to be exerted by the hand owing to hydraulic pressing of the dead center into the centering bore of the work, and the securing of the work in the fixed position 30 against dropping out by limiting the shifting movement of the hydraulically moved element.

Further objects and advantages of the invention will be hereinafter explained and are illustrated in the accompanying drawings which show 35 several embodiments of the invention.

Fig. 1 is a partial longitudinal section through the preferred form of construction, in which the pressure liquid is supplied from a separate source.

Fig. 2 shows the puppet head Fig. 1 partly in 40 cross section on line 2—2 of Fig. 1 on enlarged scale.

Fig. 3 is a partial longitudinal section through a puppet head, in which the liquid pressure is 45 produced by means of a displacer.

Figs. 4 and 5 show part longitudinal sections through puppet heads with air buffer connected to the pressure chamber.

Figs. 6 and 7 are part longitudinal sections 50 through puppet heads with contact manometer for regulation of the liquid pressure, the pressure liquid being supplied to the puppet head shown in Fig. 6 through a separate conduit, whereas in the puppet head shown in Fig. 7 the pressure of the liquid is produced by means of the displacer.

Fig. 8 is an end elevation of the puppet head shown in Fig. 7.

In the forms of construction shown in Figs. 1, 2 and 4 the dead center 4 is arranged in the pin part 1 constructed as plunger. Behind the part 1 a chamber 7 is arranged, which is designed to hold pressure liquid. The movability of the pin part 1 carrying the dead centre standing under the influence of the pressure liquid in the chamber is during the treatment at least equal to the maximum expansion of the fixed work and amounts at the utmost to about one half of the depth to which the dead center engages with the centering bore of the work. The chamber 7 is formed by the subdivision of the casing 3 by means of a stuffing box 9 provided in the chamber and formed by an annular projection in the casing. The packing of the part 1 is designated by 1' and that of the annular projection by 3'. The part 1 is secured against rotation by a key 28 fixed in this part and for which a groove 29 is provided in the casing 3, so that the axial displacement is not impeded. In the rear pin part 2 the spindle 5 fitted with a hand wheel 6 engages, which has a collar 5' and which is securely held in the casing by means of an annular disc 5'', fixed by means of screws not shown. The pin part 1 has an extension 8 extending towards the rear pin part 2 and engaging with a bore of the latter. The rear pin part 2 and the extension 8 are connected with each other by a connecting element, consisting of a wedge 10, extending through the rear part 2 and through the extension 8. The clearance 14 of the wedge 10 in the extension does not amount to more than half the depth to which the dead centre 4 engages with the centering bore 30 of the work 31. The rear pin part 2 is mechanically operated by rotation of the hand wheel 6, the front pin part being shifted after a travel amounting to the clearance 14 between the rear 45 and front pin parts. This mechanical operation serves for the introduction of the dead centre into the centering bore of the work. The dead centre is pressed into the centering bore of the work by the pressure liquid. An aperture 32 in the casing 3 serves for the removing of the coupling element 10. A manometer 26 is connected to the pressure chamber 7 and serves for controlling the liquid pressure. A hand pump 11 is provided for the production of the pressure. Instead of a hand pump a mechanically driven pump may evidently be provided. In the conduit 12 for the pressure liquid an element is located, which permits of the pressure liquid yielding and flowing forward in the chamber 7, and it consists 50 of

of a pressure regulating element 13, a multiple way cock 33 being further arranged in said conduit. The pressure regulating element 13 may consist for instance of two valves 35 and 36, operating under the action of the liquid flow (arrow 34) produced by the pump. These valves are controlled by springs 37 and have shafts merging into screw-bolts 38. On these shafts nuts 39 serving as abutments for the springs 37 are screwed so that they permit of altering the spring tension. The other abutments for the springs are formed by the casing of the pressure regulating element, a disc being eventually interposed. The pressure to which the spring is adjusted can be read on a scale 40. By the variable spring tension it is possible to adjust the pressure regulating element in accordance with any desired liquid pressure in the pressure chamber. The portion of the conduit supplying the liquid is connected at 41, whereas the portion discharging the liquid is connected at 42. In this latter portion, which leads to the collecting cup of the pump 11, the three-way cock 33 is arranged. A screw 44 is provided for putting in place and removing the valve 36. To the bore 45 of the pressure regulating element 13, leading to the pressure chamber 7, an air buffer 46 is connected, adapted to be shut off from the pressure chamber by a shutting off cock 47.

In the form of construction shown in Figs. 1 and 2 the bore 48 extends in the pressure regulating element in lateral direction. To this bore 48 the manometer 26 is connected and adapted to be shut off from the pressure chamber by a cock 49. An air cock 50 enables one to connect the air buffer with the atmosphere. In the form of construction shown in Fig. 4 the manometer 26 is connected with the air buffer 46 and is adapted to be shut off by a cock 51. A cock 52 serves for draining pressure liquid. Instead of the pump 11 a pressure accumulator can be provided. The pressure chamber 7 can also be connected with a spring loaded pressure accumulator, the spring pressure being adjusted in accordance with the pressing-on pressure to be obtained. When such an accumulator is provided, separate valves are no longer necessary. In this case the accumulator forms already the element, which permits of the moving back and forward of the pressure liquid in accordance with the dead centre displacement required for the work, without substantial pressure alteration. As such a form of construction is clear without further explanation, it is not shown in the drawings.

The form of construction illustrated in Fig. 6 differs from that shown in Fig. 4 in that instead of the simple manometer a contact manometer 57 of known type is provided, the electric wires 70 of which lead to a motor not shown, which drives a pump for the production of a pressure liquid but also not shown. Motor and pump may be arranged on the puppet head instead of the hand pump 11 shown in Fig. 2.

In the forms of construction shown in Figs. 3 and 5 the pressure chamber 7 is located in a mechanically operated pin part 2' so that this mechanically operated part forms a pressure cylinder for the hydraulically operated pin part 1''. The end of the part 2' is constructed like a screw spindle 17, guided in a sleeve 18 constructed like a nut, and on which a hand wheel 19 for the mechanical feed is mounted. A collar 18' enables one to fix in the pin casing the sleeve 18 by means of the annular disc 15. A displacer 20 is arranged in the hollow spindle 17 for producing the liquid

pressure in the pressure chamber 7, said displacer being operated by the screw spindle 21 by means of a hand wheel 25.

In the form of construction shown in Fig. 3 the device permitting of the yielding and displacing of the pressure liquid in accordance with the dead centre displacement caused by alteration of length of the work is obtained in that a spring 22 is interposed between the displacer 20 and the screw spindle 21. A manometer 23 is connected with the pressure chamber 7.

In the puppet head shown in Fig. 5 an air buffer 53 is connected with the pressure chamber 7 and serves as pressure regulating element. The manometer 54 is arranged on the air buffer and can be shut off from the pressure by means of a cock 55. The displacer 20 and the screw spindle 21 are made in one piece.

In the forms of construction shown in Figs. 3 and 5, the pin casing 3 has an opening 24 in consideration of the shifting movement of the pin part 2' at the mechanical feed. The packings on the pin part 1''' and on the mechanically moved pin part 2' are designated by 56. The wedge 10 extends through the pin part 2' and through the pin part 1''' and it has in the pin part 2' a clearance 14. This clearance does not amount to more than half the depth at which the dead centre engages with the centering bore of the work.

In the form of construction shown in Figs. 7 and 8 a contact manometer 58 of known type is substituted for the manometer 54 of Fig. 5 and connected by leads 59, 59', 59'' with a motor 60 adapted to be switched in in both directions of rotation. The sleeve 18, constructed as nut for the screw spindle 17, is driven through a worm gear 61, operated by a hand wheel 19'. A spur wheel 63 is positively connected by a key 64 with the spindle 21 of the displacer 20, said spindle being capable of shifting in axial direction during the rotation, owing to its long groove 65. A pinion 66 on the shaft of the motor meshes with the spur wheel 63. The motor revolves in the one or other directions, according to whether the contact manometer closes the electric circuit through the wires 59 and 59' or through the wires 59 and 59'', so that the displacer 20 is pulled out or pushed in according to requirement. The hand wheel 25 on the displacer spindle 21 serves for the fixing and for the operating by hand. An optical or acoustic signal may be connected with the electric circuits, said signal being lighted or sounded, as soon as the adjusted pressure of the pressure liquid alters.

The operation of the puppet head constructed according to the invention is as follows:

The dead centre is inserted by rotation of the hand wheel 6 (Figs. 1 and 4) or of the hand wheel 19 (Figs. 3 and 5) or of the hand wheel 19' (Figs. 7 and 8) into the centering bore 30 of the work 31, the mechanically operated pin part 2 and the hydraulically operated pin part 1 being pushed forward. During the mechanical feeding the three way cock 33 connects, in the forms of construction shown in Figs. 1, 2, 4 and 6, the pressure chamber 7 with the collecting cup of the pump 11, as shown in Fig. 2, in order that at the forward moving of the pin part 1 liquid may be sucked into the pressure chamber 7 and forced out of the same at the mechanical pulling back. After the completion of the mechanical pushing forward the cock 33 is turned in the direction of the arrow 66, so that the pressure chamber 7 is cut off and the bore 67 of the cock registers with the conduit 12. After the dead centre has been introduced into the

centering bore of the work, the hydraulically shiftable pin part 1 is put under hydraulic pressure, whereby the dead centre is pressed into the centering bore.

5 In the construction shown in Figs. 1, 2, 4 and 6 pressure liquid is conducted into the pressure chamber 7, whereas in the construction shown in Figs. 3, 5, 7 and 8 the pressure is produced by the plunger penetrating into the pressure chamber 10 filled with liquid. At the mechanical introducing of the dead centre into the bore a surface 63 of the wedge 10 and a surface 69 of the hydraulically operated pin part 1 are pressed the one against the other. At the pressing-in these surfaces separate. In order to completely utilize the clearance, the mechanical pin part is pulled back, after the pressing-in, a distance equal to the width of the clearance. The manometer permits of controlling whether a sufficient pressing-in 20 pressure has been attained. If, when the work has been treated, alterations of length of the work occur, which require a pressure increase in the pressure chamber 7, yielding or displacing of the pressure liquids takes place, according to 25 whether the work expands or contracts, this yielding or advancing being effected by the pressure regulating elements, so that the pressing-in pressure is never altered in a manner worth mentioning.

30 In the forms of construction shown in Figs. 1, 2, 4 and 6 the pressure equalization is effected by the pressure regulating element 13, through which liquid can flow only in the direction of the arrow 34, and the valve 36 of which, permitting the return flow from the pressure chamber, can be adjusted to a certain pressure as already stated above. If the expansion in length of the work is completed and the work contracts, the valve 36 remains closed, whereas pressure liquid 40 flows through the valve 35 into the pressure chamber 7.

In the form of construction shown in Fig. 3 a pushing back of the displacer, in opposition to the spring 22, takes place at pressure increase, 45 i. e. expansion in the work. Inversely the displacer is again pushed forward by the spring at the subsequent contraction of the work, so that the necessary pressing-in pressure is always at disposal.

50 If for any reason whatsoever the pressure of the liquid should suddenly fail or drop, the centre can never disengage completely from the centering bore, and the work cannot drop out, as the clearance 14 between the hydraulically operative 55 pin part and the mechanically operative pin part does not amount to more than half of the engaging depth of the dead centre, so that an accidental backward movement of the dead centre can also never amount to more than this half.

60 The air buffer connected to the pressure chamber, according to Figs. 1, 6 and 7 neutralizes short pressure increases, for instance vibrations at rough turning up to the pressure limit determined by the overloading valve of by the contact 65 manometer.

In the puppet head shown in Fig. 5 the air buffer 53 forms the element, which permits of the advancing and yielding of the liquid according to the dead centre displacement, due to 70 the alteration in length of the work. The air buffer may evidently be further connected to a compressed air conduit or an accumulator of compressed air, in the conduit of which, corresponding with the pressure regulating element 75 13 in the liquid conduit in the form of construc-

tion shown in Fig. 2, a pressure regulating element is built, which equalizes fluctuations of pressure.

The form of construction shown in Fig. 5 and in Fig. 3 is specially suitable for turning lathes of medium size.

The contact manometer connected with the air buffer in the form of construction shown in Fig. 6 switches in at pressure drop a motor not shown, which drives a pump, supplying a pressure liquid for the pressure chamber.

In the form of construction shown in Fig. 7 the contact manometer switches in a motor for both directions of rotation, which either pulls out or pushes in the displacer 20 according to requirement. The contact manometer might be directly connected with the pressure chamber.

For releasing the work, the pressure is removed from the pressure chamber and then the dead centre pulled back mechanically.

The releasing of the work can evidently be effected in the form of construction shown in Figs. 3, 5, 7 and 8 also by mechanical pulling back without a pressure drop.

The invention is not limited to the forms of construction shown.

I claim:—

1. A puppet head, comprising in combination a casing having a central longitudinal bore, a two part dead centre carrier in said casing composed of a front part and a rear part longitudinally shiftable in said casing, an extended axle extending towards the interior of said casing and having a screw thread, a dead centre pin carried in the front end of said carrier part the rear part of said carrier having a screw thread engaging the screw thread of said extended axle a wheel on the end of said casing adapted to rotate said extended axle and shift said rear carrier part in said casing, a pressure liquid chamber at the rear end of said front carrier part adapted to act on the rear end of said front carrier part, a coupling element connecting said front and rear carrier parts with play extending plunger like into said chamber adapted to transmit the movement of said rear carrier part imparted by said extended axle to said front carrier part and to press said dead centre pin into the work, and a device communicating with said chamber adapted to allow the automatic yielding and returning of the liquid in said pressure chamber and consequently a displacement of said front carrier with said dead centre pin according to the alterations in length of the work.

2. A puppet head as specified in claim 1, in which an air cushion is connected to the liquid filled pressure chamber acting on the front carrier part accommodating the dead centre pin on the same side of said front carrier part on which said liquid acts, said air cushion acting on said liquid and having the same pressure as that of the liquid.

3. A puppet head, comprising in combination, a casing having a central longitudinal bore, a two part dead centre carrier in said casing composed of a front part and a rear part longitudinally shiftable in said casing, an extended axle extending towards the interior of said casing and having a screw thread, a dead centre pin carried in the front end of said carrier part the rear part of said carrier having a screw thread engaging the screw thread of said extended axle a wheel on the end of said casing adapted to rotate said extended axle and shift said rear carrier part in said casing, a stuffing box in said casing

between said carrier parts dividing the bore in said casing into two parts, a piston rod extension on the rear end of said front carrier part extending through said stuffing box, a coupling element connecting said piston rod like extension with play to the front end of said rear carrier part, a chamber filled with liquid between the rear side of said front carrier part and the front of said stuffing box adapted to act on said front carrier part in the feed direction, and a device connected to said chamber adapted to allow the yielding and returning of the liquid in said chamber and a displacement of said front carrier part with said dead center pin according to the alterations in length of the workpiece during the working.

4. A puppet head as specified in claim 1, in which the hydraulic shiftability of the front carrier part relative to the rear carrier part is equal to at least the maximum expansion of the workpiece and does not exceed one half of the depth of engagement of the dead centre pin in the centring bore in the workpiece.

5. A puppet head as specified in claim 1, in which the play between the two carrier parts rendered possible by the coupling element does not exceed one half of the depths of engagement of the dead centre pin in the centering bore in the workpiece.

6. A puppet head as specified in claim 1, comprising in combination with the dead centre pin, the front carrier part and the rear carrier part, a transverse pin extending through both of said carrier parts connecting said carrier parts with a certain amount of play not exceeding one half of the depth of engagement of said dead centre pin in the centering bore in the workpiece.

7. A puppet head, comprising in combination a casing, a dead centre, a two part dead centre carrier shiftable in said casing composed of a front part carrying said dead centre and a shiftable rear part having a screw thread, an extended axle extending into said casing and having a screw thread engaging the screw thread of said rear part, a wheel on said axle at the rear end of said casing adapted to rotate said axle to shift said rear part in said casing, a coupling element connecting said carrier parts with play adapted to transmit the movement of said rear carrier part to said front carrier part, said front carrier part being constructed as cylinder and containing pressure liquid and said rear part constructed as plunger adapted to press said front part against the work piece, and a device connected to said cylinder adapted to allow the liquid to automatically escape from and return into said cylinder according to the variations in length of the work piece during the working operation.

8. A puppet head, comprising in combination a casing, a dead centre, a two part dead centre carrier shiftable in said casing composed of a front part carrying said dead centre and a shiftable rear part having a screw thread, an extended axle extending into said casing and having a screw thread engaging the screw thread of said rear part, a wheel on said axle at the rear end of said casing adapted to rotate said axle to shift said rear part in said casing, a coupling element connecting said carrier parts with play adapted to transmit the movement of said rear carrier part to said front carrier part, said front carrier part being constructed as cylinder and containing pressure liquid and said rear part constructed as plunger adapted to press said front part

against the work piece, and a device connected to said cylinder adapted to allow the liquid to automatically escape from and return into said cylinder according to the variations in length of the work piece during the working operation said front part having a longitudinal bore with screw thread at its rear end and communicating with said cylinder, a displacer in said bore, a screw spindle engaging in the screw thread of said bore carrying said displacer on its front end extending through said wheel on the rear end of said casing, and a second wheel on the rear end of said spindle adapted to displace said displacer in said bore to regulate the pressure in said cylinder.

9. A puppet head, comprising in combination a casing, a dead centre, a two part dead centre carrier shiftable in said casing composed of a front part carrying said dead centre and a shiftable rear part having a screw thread, an extended axle extending into said casing and having a screw thread engaging the screw thread of said rear part a wheel on said axle at the rear end of said casing adapted to rotate said axle to shift said rear part in said casing, a coupling element connecting said carrier parts with play adapted to transmit the movement of said rear carrier part to said front carrier part, said front carrier part being constructed as cylinder and containing pressure liquid and said rear part constructed as plunger adapted to press said front part against the work piece, a liquid chamber in said casing adapted to act on the rear end of said front carrier, a device connected to said chamber adapted to allow an automatic yielding and displacing of the liquid in said chamber and a moving back of said front carrier part according to the variations in length of the workpiece, a pressure gauge connected to said pressure chamber adapted to indicate the pressure in said chamber, electric contacts in said pressure gauge, a circuit connected to said contacts adapted to be closed by said contacts when the pressure drops in said chamber and to be broken when a certain pressure is reestablished and an electric pressure producer connected up in said circuit adapted to be actuated by the closing of said circuit to reestablish the pressure in said chamber and to be again cut out when the pressure is reestablished in said chamber.

10. A puppet head, comprising in combination a casing, a dead centre, a two part dead centre carrier shiftable in said casing composed of a front part carrying said dead centre and a shiftable rear part having a screw thread, an extended axle extending into said casing and having a screw thread engaging the screw thread of said rear part, a wheel on said axle at the rear end of said casing adapted to rotate said axle to shift said rear part in said casing, a coupling element connecting said carrier parts with play adapted to transmit the movement of said rear carrier part to said front carrier part, said front carrier part being constructed as cylinder and containing pressure liquid and said rear part constructed as plunger adapted to press said front part against the work piece, and a device connected to said cylinder adapted to allow the liquid to automatically escape from and return into said cylinder according to the variations in length of the work piece during the working operation said front part having a longitudinal bore with screw thread at its rear end and communicating with said cylinder, a displacer in said bore, a screw spindle engaging in the screw thread of said bore carrying said displacer on its front end extending
